UNITED STATES PATENT OFFICE.

RANSOM COOK, OF SHELBURNE FALLS, MASSACHUSETTS.

MACHINE FOR TURNING THE LIPS OF AUGERS.

Specification of Letters Patent No. 12,583, dated March 27, 1855.

To all whom it may concern:

Be it known that I, RANSOM COOK, of Shelburne Falls, in the county of Franklin and State of Massachusetts, have invented a new and useful machine for facilitating the manufacture of certain boring implements by turning the lips or cuts of such implements with great expedition and accuracy; and I do hereby declare that the following is a full, clear, and exact description of the construction and operation of the same, reference being had to the annexed drawings, making a part of this specification, in which—

15. Figure 1, is a longitudinal elevation; Fig. 2, a transverse section; Fig. 3, a face view of the wrench; Fig. 4, a side view of the same; Fig. 5, an end view of a boring implement with the lips turned; Fig. 6, an elevation of a boring implement with the lips turned; Fig. 7, an elevation of the same implement before the lips are turned.

Letter *a*, marks a crimping die; *b*, the clamps or chops in which the crimping dies are set; *c*, the cam-lever; *d*, the wrench wheel; *e*, *e*, *e*, *e*, handles to the wrench wheel; *f*, the screw-shaft; *g*, the hand wheel; *h*, *h*, the standards or pillar blocks supporting the shaft; *i*, the bed plate.

30. In constructing the machine, (which is independent of the form on which it stands) I make it entirely of iron and steel. The wrench, the screw-shaft and some of the bolts of steel; the handles to the wrench wheel, some of the bolts and the band around the chops of wrought iron and all the remaining parts of cast iron.

The crimping or clamping dies *a*, are so shaped that one side of them shall fit into the twist of the auger or bit, in order that when two of them are pressed together with the auger between them, they shall embrace nearly its entire surface as far as they extend on its length and thus hold it very firmly.

45. The chops or clamps *b*, have each a recess near the top in which to secure the crimping dies. The chops are connected at their lower ends by a joint in a manner similar to the ordinary blacksmiths vice. A strop of iron embraces the chops and is connected with the cam lever *c*, by a bolt which passes

through the ends of the strop and through the cam-lever at such distance from its end that when brought to a horizontal position 55 it will press the chops most closely together.

The wrench wheel *d*, is fitted on the end of the screw-shaft in such a manner that it may be freely turned, toward or from the workman using it, without turning the shaft. 60 Slots are cut in the hub of the wheel in which the wrench is secured. Handles *e*, *e*, *e*, are inserted in the periphery of this wheel for the purpose of turning it.

The wrench, Figs. 3 and 4, and marked 65 in the drawings of the wheel 3, 4, where it is shown as inserted in the hub, has a hole in its middle for the purpose of receiving the center of the auger, and slots cut on each side of the hole to receive the lips of the 70 implement. It is inserted in the hub of the wheel with its face, as shown in Fig. 3, toward the crimping dies. The screw-shaft *f*, is moved, by means of the screw, to the right or left as it may be turned; carrying the 75 wrench and wrench wheel along with it. The hand wheel *g*, is attached firmly to the screw shaft and used for turning it.

In using this machine, the cam-lever is first raised to nearly a vertical position, thus 80 allowing the clamps to open. An auger or bit, with the pod twisted and lips shaped as shown in Fig. 7, being heated red hot, is then placed in one of the crimping dies, with the lips projecting beyond the die and 85 toward the wrench. The upper end of the cam-lever is then brought quickly down, thus forcing the other crimping die against the auger and firmly holding it between the two dies. A quick turn is then given to the 90 screw shaft which brings the wrench in the hub of the wrench wheel, into an embrace with the end of the auger, the center of which enters the hole in the wrench while the lips pass into the slots on its side. The 95 workman then seizes one of the handles to the wrench wheel and turns it toward himself, when the wrench, keeping the auger straight by means of its hold of the center, turns or bends the lips into the desired position, both being turned at the same time and at the same angle, while the shoulders of both are left in the same line.

I do not claim as new any of the several

and separate parts of the machine herein described except the wrench; but

What I do claim as new and desire to secure by Letters Patent, is—

5 The combination of the screw shaft or its equivalent, with the wrench and crimping or clamping dies, as herein substantially set forth and for the purpose mentioned.

2. I also claim the shape of the wrench substantially as described for the purpose 10 of turning the lips of boring implements.

RANSOM COOK.
